UNITED STATES PATENT OFFICE.

JOHN ARTHUR KAYE, OF SAULT STE. MARIE, ONTARIO, CANADA.

BOTTLE CAP.

Application filed January 8, 1925. Serial No. 1,224.

The present invention relates to a closure for bottles, jars and like containers and has for its object to provide a closure of this character which embodies novel features of construction whereby the mouth of the bottle or container is effectively closed and at the same time surrounding portions of the neck are protected by a skirt portion, so that there is no danger of the contents of the receptacle being contaminated.

Further objects of the invention are to provide a bottle closure which is comparatively simple and inexpensive in its construction, which can be used repeatedly, and which has a skirt portion which can be partially or entirely replaced whenever such becomes necessary.

One particular form or embodiment of the invention is shown and described in detail for illustrative purposes, although it will be understood that many modifications and changes can be made in the details of construction and that I do not restrict myself to the exact form of the invention which is shown on the drawings.

For a full understanding of the invention reference is to be had to the following description and accompanying drawings, in which,

30 Figure 1 is a perspective view of a bottle neck which is provided with a closure constructed in accordance with the invention.

Figure 2 is a top plan view thereof.

Figure 3 is a vertical sectional view 35 through the bottle neck with the closure applied thereto.

Figure 4 is a detail view of one of the skirt sections,

40 Figure 5 is a plan view of the closure showing the same with the skirt sections arranged in the position assumed preparatory to applying the closure to a bottle.

Figure 6 is an enlarged detail view of the operating screw and a pair of the clamping arms.

45 Corresponding and like parts are referred to in the following description and indicated on all of the views of the drawings by like reference characters.

50 Referring to the drawings, the numeral 1 designates a cap member which may be formed of any suitable material such as wood, hard rubber or the like and which is adapted to be applied to the mouth of a bottle 2 or like container. The cap is formed with an annular grooved seat 1^a which is

adapted to receive and fit over the mouth of the bottle. A depending flange 3 extends around the cap just within the periphery of the grooved seat and is adapted to project 60 downwardly a short distance within the bottle neck and fit against the interior of the bottle so as to insure a tight closure when the cap is applied to the bottle. The outer edge of the cap extends over the top of the 65 bottle neck and is tapered toward the periphery so as to avoid any objectionable sharp corners.

The cap is provided with a skirt member 70 which is formed in sections and which extends downwardly on the exterior of the bottle neck so as to cover and protect the same from contamination while the bottle is being handled after the cap has been applied thereto. In the present instance the skirt 75 comprises four sections 4 which are similar and interchangeable in size and shape. One of these skirt sections is shown in detail by Figure 4, and these skirt sections may be formed of any suitable flexible material such 80 as tough fabric or cardboard which has the necessary toughness and wear resisting qualities. The upper ends of these skirt sections extend over the top of the cap 1 and may be provided with perforated ears 5 85 which are engaged by a screw 6. This screw is applied to the center of the cap 1, and can be readily tightened or loosened, being removable to permit of replacing any one or 90 more of the skirt sections.

The outer ends of the skirt sections have an overlapping arrangement and are of a sufficient width to extend completely around the exterior of the bottle neck when they are spread out evenly and folded downwardly 95 against the same. The outer ends of the skirt sections are preferably formed with the transversely disposed corrugations or crimped portions 7, and the corrugated portions of overlapping edges of the skirt sections interlock with each other when the skirt sections are folded around the bottle neck, cooperating to provide annular channels or seats within which elastic bands 8 can be fitted. The inner faces of the skirt 100 sections may or may not be provided with an adhesive, just as may be preferred, and when the skirt sections are folded downwardly around the exterior of the bottle neck, as indicated by Figures 1 and 3, the 110 elastic bands 8 are applied to one or more of the grooved seats formed by the corruga-

tions 7. These elastic members hold the skirt sections tightly against the bottle neck and when it is desired to lift the skirt sections preparatory to removing the cap, the elastic bands 8 are either removed from the bottle or disengaged from the skirt and moved downwardly below the same.

A series of arms 9 are applied to the top of the cap and engaged by the screw 6, said 10 arms terminating in downwardly extending fingers or claws 10 which are adapted to grip the bead 11 surrounding the top of the bottle neck. The arms 9 extend over the upper ends of the skirt members and assist 15 in retaining the same in position, and the claws 10 are adapted to be drawn into a firm engagement with the bottle neck so as to hold the cap securely in position thereon. The screw 6 has a knurled head 6^a which can 20 be grasped by the fingers when manipulating the same. The base of the finger piece is formed with a cylindrical portion 13 and a conical or tapered portion 14, and the inner ends of the arms 9 terminate in 25 rings 15 which are just the proper size to fit over the cylindrical portion 13, although there is a considerable amount of looseness or play when the rings surround the threaded portion of the screw.

30 The cap 1 may be provided with a bushing 16 to receive the screw and when the screw is loosened the rings 15 surround the reduced and threaded portion of the screw so that they have a sufficient amount of play to release the claws 10 from engagement with the bottle neck or permit the claws to slide outwardly a sufficient amount so that they can easily be brought into operative position. When the screw is tightened the reduced or conical portion 14 operates as a 40 wedge to forcibly bring the rings 15 into engagement with the cylindrical portion 13 of the screw, thereby drawing the claws 10 inwardly and causing them to firmly engage the bead 11. The screw 6 serves to hold the bars 10 and skirt sections 4 in position on the cap, and in the event any one or more of the skirt sections become damaged, the damaged sections can be readily removed and 50 replaced by new sections, so that the closure can be readily kept in proper repair for repeated use.

The skirt sections 4 are pivotally engaged at their upper ends by the screw 6 and all 55 of the skirt sections can be swung around into registry with each other so as to mutually protect one another and enable the device to be stored or packed in a small amount of space when it is not in use. Preparatory to using the cap the skirt sections 60 4 are swung around so that they are arranged symmetrically about the axis of the cap, as illustrated by Figure 4. With the screw loosened the cap 1 may then be properly fitted upon the bottle neck and the va-

rious skirt sections folded downwardly against the exterior of the bottle neck in the manner indicated by Figure 1. After the cap has been applied to the bottle neck the screw 6 is tightened, thereby drawing 70 the bars 8 inwardly and causing the claws 10 to engage the bead 11 of the bottle neck. The elastic bands 8 are also fitted in the grooves provided by the corrugations 7 of the skirt members. The cap is thus held 75 tightly in position and the exterior of the bottle neck is covered and protected by the skirt so that it will be free from contamination by handling or coming into contact with other objects. This is believed to be a 80 feature of considerable importance because the average bottle closure merely seals the bottle without covering or protecting any of the exterior portions of the bottle neck. These exterior portions may become infected 85 while being handled and the contents of the bottle are very frequently brought into contact with exterior portions of the bottle when the contents are being poured out for use. Thus they may readily become infected or 90 contaminated regardless of any extreme caution which is originally used in filling and sealing the bottle.

Having thus described my invention what I claim as new and desire to secure by Letters Patent of the United States is,

1. A bottle closure including a cap adapted to fit the mouth of a bottle, a skirt member formed of a series of separate sections, and a pivotal connection between the skirt sections and the cap whereby the skirt sections can either be swung into a superposed relation when not in use or spread out so as to extend over the mouth of the bottle when in use.

2. A bottle closure including a cap adapted to fit the mouth of a bottle, and a skirt member carried thereby and comprising a series of separate sections which can either be brought together in a superposed relation or spread out so as to fit over the bottle neck in an overlapping relation.

3. A bottle closure including a cap adapted to fit the mouth of a bottle, a skirt member formed of a plurality of similar and interchangeable sections, and fastening means pivotally connecting the skirt members to the cap whereby they can be swung around into a superposed relation when not in use or caused to extend in different directions from the cap so as to assume an overlapping relation when folded against the bottle neck.

4. A bottle closure including a cap adapted to fit the mouth of a bottle, and a skirt member formed of a series of similar and interchangeable sections, the edges of the skirt sections overlapping each other and having portions which interlock.

5. A bottle closure including a cap, a fas-

tening member applied to the top of the cap, and a plurality of skirt sections which are pivotally connected at their upper ends to the fastening member, so that they can 5 either be brought together in a superposed relation or spread apart to fit around the neck of a bottle in an overlapping relation.

6. A bottle closure including a cap 10 adapted to fit the mouth of a bottle, a skirt member formed of a plurality of independent sections having overlapping edge portions, said overlapping edge portions being formed with corresponding pressed out portions which have a telescoping engagement with each other, and a fastening band 15 extending around the skirt sections and engaging the said pressed out portions.

7. A bottle closure including a cap 20 adapted to fit the mouth of a bottle, a skirt member formed of a plurality of independent sections having overlapping edge portions, said skirt sections having transverse corrugations pressed therefrom and the corresponding corrugations of overlapping edge portions telescoping with each other, and a fastening band extending around the skirt member and engaging the corrugations.

8. A bottle closure including a cap 25 adapted to fit the mouth of a bottle, arms carried by the cap and provided with claws adapted to engage the bottle, a screw for securing the arms to the cap, and means ac-

30 tuated by rotation of the screw for sliding

the arms longitudinally and bringing the claws forcibly into operative position.

9. A bottle closure including a cap 35 adapted to fit the mouth of a bottle, arms applied to the cap and provided with claws 40 adapted to engage the bottle, a screw for securing the arms to the cap, and wedge means actuated by the screw for forcibly sliding the arms longitudinally to bring the claws into operative position. 45

10. A bottle closure including a cap 50 adapted to fit the mouth of a bottle, arms carried by the cap and provided with claws adapted to engage the bottle, said arms being provided with rings, a screw, and a 55 tapered portion on the screw adapted to co-operate with the rings to slide the arms longitudinally and bring the claws forcibly into operative position.

11. A bottle closure including a cap 55 adapted to fit the mouth of a bottle, a skirt member formed of a plurality of independent sections of which the upper ends extend over the top of the cap and are provided with eyes, while the lower ends are 60 adapted to fit around the bottle neck in an overlapping relation, arms applied to the top of the cap and fitting over the skirt members, and a screw fastening the arms to the cap and extending through the eyes of the 65 skirt sections.

In testimony whereof I affix my signature.

JOHN ARTHUR KAYE.
